CHARLES M. GAGE, JR., OF EAST PEPPERELL, MASSACHUSETTS.

PAPER DRINKING-CUP.

1,039,723.

Specification of Letters Patent.

Patented Oct. 1, 1912.

Application filed March 30, 1912. Serial No. 687,308.

To all whom it may concern:

Be it known that I, CHARLES M. GAGE, Jr., a citizen of the United States, and resident of East Pepperell, county of Middlesex, 5 State of Massachusetts, have invented an Improvement in Paper Drinking-Cups, of which the following description, in connection with the accompanying drawing, is a specification, like characters on the drawing 10 representing like parts.

This invention has for its object the production of an improved hygienic paper drinking cup of the single-service type, such as are used in various public places in connection with drinking water tanks, the cup constructed in accordance with my invention having a smooth, rounded drinking edge or lip which also stiffens the open end of the cup and enables a single cup at a time to be 20 removed from the usual holders in which a supply of the cups is commonly kept.

The various novel features of my invention will be fully described in the subjoined specification and particularly pointed out in 25 the following claim.

The drawing represents in elevation and vertical section a drinking cup embodying my invention, the thickness of the wall of the cup body being exaggerated.

30 The drinking cup embodying my invention is shown as comprising a tubular and slightly tapered body 1 of thin and tough paper of suitable quality, the longitudinal edges of the blank being overlapped at 2 and suitably united, the body being permanently closed at one end by a stiff disk 3 of paper. Herein the bottom is held in place between an annular bead 4 formed in any suitable manner on the interior of the body, 35 and a continuous annular and transversely convexed lip 5. This lip is formed by rolling the lower edge of the body over inwardly upon itself, by any suitable means forming no part of my present invention.

40 The disk 4 is in practice pushed downward into the body from its open upper end and snapped into place between the bead 4 and the lip 5, and is securely held in place therebetween in a water-tight manner by a

50 coating of paraffin or other suitable moisture-repellant waxy material, applied while hot and fluid by immersing the cup in a bath of the molten coating material and removing and quickly cooling the coated cup.

The cup is preferably coated in accordance with the process forming the subject matter of United States Patent No. 1,007,086 granted to C. M. Gage on the 31st day of October, 1911.

Heretofore drinking cups of this general character have been made with a sharp edge around the open end thereof, or in some cases they have been made with a light wire encircling the open end, to stiffen the body of the cup and facilitate handling thereof. 60 Such a construction, if the wire is used, adds very materially to the cost of construction, and the cups cannot be manufactured and sold commercially at the small price demanded, and when the edge is left plain the 65 cup is not stiff enough to be handled conveniently, nor is it pleasant to drink from, owing to the sharp edge. Furthermore, when such cups are nested in the holders it often happens that more than one cup will 70 be drawn out when a user desires to remove a cup from the holder. I obviate these objections by rolling over the edge of the body at the open end to form a continuous 75 annular and transversely convex lip 6, similar to the lip 5, but out-turned, whereas the lip 5 is rolled over inwardly, as shown.

When the cup is dipped in the coating material and then removed from the bath the lip 6 forms a receptacle which receives and 80 retains quite an amount of the coating material, the latter when it hardens serving to stiffen the open end of the cup in a very superior manner. This lip gives a much better and pleasanter drinking edge, the cup 85 when filled with water is stiff enough to be handled easily and conveniently, and as the lip 5 is out-turned it prevents nested cups from fitting together too snugly, and more than one at a time cannot be withdrawn. 90 Obviously the bottom lip 5 will also receive and hold some of the coating material, and the bottom of the cup will thereby be stiffened and strengthened in a manner similar to that described with relation to the lip 6, 95 but this is not so important at the lower end of the cup, as the bottom 3 stiffens the body therat.

The formation of the lip 6 is effected very readily, adding practically nothing to the 100 cost of production, and the filling up of the receptacle formed by such lip, with the coating material, requires no extra care or at-
